Walton Harrison.

UNITED STATES PATENT OFFICE.

SAMUEL DAVIS ROBINS, OF STAMFORD, CONNECTICUT.

TORPEDO-SHIELD.

1,266,715.

Specification of Letters Patent. Patented May 21, 1918.

Application filed July 14, 1917. Serial No. 180,635.

To all whom it may concern:

Be it known that I, SAMUEL DAVIS ROBINS, a citizen of the United States, residing at Stamford, in the county of Fairfield and 5 State of Connecticut, have invented certain new and useful Improvements in Torpedo-Shields, of which the following is a full, clear, and exact description.

My invention relates to torpedo shields of 10 a kind adapted to be carried by a ship for the purpose of preventing torpedoes and floating missiles from reaching the hull of the vessel.

More particularly stated, my invention 15 comprehends a number of separate metallic plates, carried by the ship, and spaced from the hull thereof, each plate while in use extending into the water and being so formed and mounted as to possess a certain amount 20 of flexibility or freedom of movement, and yet to maintain a proximate normal vertical position of great stability while the ship is traveling ahead. In other words, the plates are so suspended in the water that, as the 25 ship moves forward, the drag of the water upon each plate has a tendency to hold the plate in stable equilibrium. Each plate is thus so arranged that any departure from its normal position is characterized by an 30 increased amount of resistance or drag.

In order that the principle underlying my invention may be readily understood, I will explain briefly some of the difficulties which have been found to exist and which I seek 35 to overcome.

In the construction of a torpedo shield of the general type here contemplated, there is advantage in using a number of separate metallic plates, each of homogeneous form 40 and mounted with a certain degree of flexibility or freedom of movement relatively to other plates and to the hull of the vessel. If the plates are allowed too much freedom of movement, however, they cease to be effective as shields, and various other troubles 45 are likely to develop. It is a difficult matter to so arrange the plates that they will operate equally well whether the vessel be stationary or moving ahead, and whether the 50 speed of the vessel be rapid or slow.

The reason for allowing the plates a limited amount of freedom of movement is to prevent undue strains upon the ship and the hoisting gear associated with the plates, and 55 also to avoid affecting the course of the vessel. To allow for the rolling and lateral

movements of the vessel, the plates must be allowed freedom to swing.

In some instances the plates have each been hung from horizontal hinges to which the plate was connected by its upper edge. It was found by trial, however, that with this arrangement the plates did not have enough stability. They came to the surface whenever the vessel changed its course, or 60 even when the plates were subjected to the almost constant action of waves, swells and eddies. In fact, it was found impossible to keep them in vertical position, at any time.

If the plate be mounted upon vertical 70 hinges connected to its forward edge instead of its top edge the plate will trail properly with the vessel in motion or even changing its course, but in this event the plate does not hang in stable equilibrium by its own weight 75 and this arrangement offers no protection against a torpedo when not in a fore-and-aft position.

Again, if the plate be supported by a special mounting, so as to hang from one edge 80 and also to trail rearwardly, a complication of mechanism is necessitated which causes many troubles to make their appearance.

By my invention I seek to suspend the plate from hinges connected to only one of 85 its edges, the form and arrangement of the parts being such that the plate is given all necessary freedom of movement, and yet is by its own weight and the resistance of the water held in a correct vertical position. 90 Thus the plate never deviates beyond proper limits from a given position in which it affords a maximum of shielding effect, and this remains true independently of whether the vessel be stationary, moving ahead 95 slowly or rapidly, sailing in a straight line, or abruptly changing course.

In order to avoid undue prolixity, I will show and describe merely a single form of my invention, it being understood, however, 100 that the form presented is merely typical, and that the invention may assume any other form contemplated by the law of equivalents.

Reference is made to the accompanying drawing forming a part of this specification, 105 and in which like letters indicate like parts in all of the figures.

Figure 1 is a fragmentary side elevation of a ship equipped with this improved torpedo shield.

Fig. 2 is a substantially central cross section through the ship and shows how the 110

plates are supported and spaced from the sides thereof.

Fig. 3 is a fragmentary perspective of one of the plates and its mountings.

The hull of the vessel appears at 4, the rudder thereof being shown at 5 and the propeller at 6.

The vessel is shown as traveling to the left according to Fig. 1, as indicated by the arrow shown in this figure.

A number of metallic plates 7 are each provided with a bottom edge 8, a top edge 9, a forward edge 10 and a rear edge 11. The forward edge 10 is parallel to the rear edge 11 and these edges are each perpendicular to the bottom edge 8. The top edge 9, however, is inclined relatively to the other edges, so as to slant forwardly downward when the plate is in position.

Each plate is so mounted as to swing upon an axis the projection of which upon the plane of the sea is parallel to the keel of the ship, the axis being inclined, however, so that its forward end is lower than its after end.

While the object just stated is quite essential, the particular mechanism whereby the plate is supported for the purpose is a matter of minor importance. In the particular instance here illustrated, each plate 7 is provided with a pair of eyes 12, and extending through these eyes is a rod 13. The ends of this rod extend through the outer or free ends of two arms 14, 15. The opposite ends of these arms are by means of bearings 16, 17 journaled to the side of the vessel. Cross braces 18, 19 extend from one of the arms to the other, and serve to prevent these arms from swinging except in planes contemplated by the form of the bearings 16, 17.

Connected to the outer or free ends of the arms 14, 15 are cords 20, 21, which engage pulleys 22, 23 and together therewith constitute the hoisting gear for raising and lowering the plate.

The parts are shown as in normal position. The plates are now down, and each extends into the water 24 to a suitable depth, which may be different for ships of different size and character, and may be varied by aid of the hoisting gear.

By pulling upon the cords 20, 21 the plate may be raised out of the water. The cords 20, 21 are arranged in pairs, one pair for each plate, so that the plates may be raised or lowered independently of the others.

The arms 14, 15 may be of any length desired, but are preferably about twenty feet long.

The operation of my device is as follows:—

So long as the vessel remains stationary, little difficulty is experienced with the plates, as each simply hangs by its own weight.

Swells, waves and eddies cause the plates to

swing more or less, but not enough to diminish materially the shielding effect of the plates.

Suppose, next, that the vessel is moving to the left according to Fig. 1, as indicated by the arrow. The forward motion of the vessel of course causes the water to exert a drag upon the plates. Each plate thus has a tendency to trail, because the forward support for the plate is a little lower than the after support.

To the extent that the plate swings laterally, it swings upon an axis the projection of which, upon the plane of the sea, is parallel to the heel of the ship, but the forward end of which is lower than its after end. To the extent that the plate swings laterally, it must swing upon the axis just mentioned, and in so doing is necessarily carried a trifle forward. Therefore any departure of a plate from its normal vertical position is characterized by an increase in the resistance or drag of the water, and the plate is thus effectively stabilized.

To make the application of this principle clear, glance at any one of the plates shown in Fig. 1, and imagine such plate to be turned, upon its axis of rotation just mentioned, until completely inverted. It will be found that the turning of the plate is accompanied by a slight forward displacement of the plate, relatively to the hull of the ship. Therefore the plate while hanging naturally in its lowermost position is always in its extreme position toward the rear and therefore in its position of greatest stability. In other words, the position which the plate tends to assume in consequence of its being dragged forwardly through the water is the same position it tends to assume from its own weight, even if the ship be stationary and this is the vertical position. Thus the action of gravity and the motion of the vessel coincide to hold the plate in a vertical position of stable equilibrium. This vertical position of the plate is the only one in which the plate is subjected to a minimum of resistance by the water. Any deviation of the plate from its normal or vertical position increases the resistance of the water.

Thus while the plate has sufficient flexibility or freedom of motion to enable it to move or yield when necessary, it does not move to a sufficient extent to seriously impair its function in shielding the ship as against attacks by torpedoes.

The manner in which torpedoes are caused to explode in striking a barrier of any kind is well-known, and needs no description here. My shield, made up of plates of the kind above described, acts for this purpose like any other barrier against which a torpedo is discharged.

I do not limit myself to the precise hoist-

ing or supporting mechanism here shown, as variations may be made therefrom without departing from the spirit of my invention, as defined in my claims.

5 I claim:—

1. The combination, with a ship, of a plate carried thereby and hanging loosely by its own weight into the sea, said plate being so suspended that when the ship moves forward the drag of the water upon the plate 10 has a tendency to force the plate into a vertical position if accidentally displaced therefrom.

2. The combination, with a ship, of a plate 15 supported by said ship and hanging into the sea for the purpose of preventing torpedoes from striking said ship, said plate being mounted to swing upon an axis whose projection upon the plane of the sea is parallel 20 to the keel of the ship, the forward end of said axis being lower than its after end.

3. In a device of the character described 25 the combination, with a ship, of a pair of arms mounted thereupon and extending laterally therefrom, and a plate supported by said arms and mounted to swing upon an axis whose projection upon the plane of the sea is parallel to the keel of the ship, the forward end of said axis being lower than 30 the after end thereof.

4. The combination of a sea-going vessel, a plate disposed parallel thereto and extending into the sea, and means for so supporting said plate from said vessel that as said 35 vessel travels through the water the backward drag of the water upon said plate holds said plate in stable equilibrium.

5. The combination of a ship, a plate disposed adjacent thereto and extending into 40 the sea, and means for so supporting said plate from said ship that said plate normally maintains a predetermined position of great stability, any departure from said predetermined position tending to increase 45 the drag of said plate as it is drawn through the water.

6. The combination of a sea-going vessel, arms journaled thereupon and overhanging the sea, one of said arms being located slightly higher than another, a rod supported by said arms and inclined relatively 50 to the horizon, the lower end of said rod extending in the normal direction of forward travel of said vessel, and a protecting plate carried by said arms and depending into 55 the sea.

7. The combination, with a ship, of a plurality of protecting plates supported by said ship and hanging into the sea for the purpose of preventing torpedoes from striking 60 said ship, each plate being mounted to swing upon an axis whose projection upon the plane of the sea is parallel to the keel of the ship, the forward end of said axis being lower than the after end thereof, and 65 means for raising and lowering said plates independently of each other.

8. The combination of a sea-going vessel, arms journaled thereupon and overhanging the sea, the after one of said arms being 70 located slightly higher than the other, an axis supported by said arms at their outer extremities and inclined at a suitable angle with the waterline, the forward end of said axis being lower than the after end thereof, 75 a protecting plate of suitable dimensions supported by said axis and hanging into the sea, hoisting and adjusting mechanism connected with said plate and controllable from said ship for raising and lowering said 80 plates independently of each other.

9. The combination, with a ship, of a plate carried thereby and hanging loosely by its own weight into the sea so that when the ship is stationary said plate occupies a pre-determined normal position, said plate being 85 so suspended that when the ship moves forward the drag of the water upon the plate has a tendency to restore said plate to said normal position whenever accidentally displaced therefrom.
